DOUBLE CASING PUMP

Filed Oct. 26, 1949

UNITED STATES PATENT OFFICE

2,668,503

DOUBLE CASING PUMP

Hugh L. Ross, Shorewood, Wis., assignor to Allis-Chalmers Manufacturing Company, Milwaukee, Wis., a corporation of Delaware

Application October 26, 1949, Serial No. 123,768

1 Claim. (Cl. 103—111)

1 This invention relates to multiple stage double casing pumps. More specifically this invention relates to that type of double casing pump especially designed for pumping liquids at relatively high pressure and temperature. The principal object of this invention is the provision of a new and improved liquid pumping machine.

The double case type pump generally comprises an inner pumping casing that is spaced within an outer pressure casing. The inner casing contains impellers and annular passages for guiding the liquid through the pumping stages. The outer casing is generally divided by an annular projection into an intake chamber and a discharge chamber. The inner casing is fitted within the outer casing and is seated against the annular projection with the first stage impeller or impellers taking suction from the intake chamber and discharging the liquid after passing through all of the stages into the discharge chamber of the outer casing. The intake end of the inner casing is held tight against the annular seat by the discharge pressure in the discharge chamber. This leaves the end of the inner casing remote from the annular seat free to move axially relative to the outer casing as the inner casing expands and contracts in response to changes in temperature and/or pressure within.

The invention is especially useful when applied to pumps supplying feed water to boilers at high temperature and pressure. Under such circumstances the axial movement of the inner casing relative to the outer casing may be quite substantial and frequent as changes in demand are made upon the pump. Accordingly, it is a primary object of this invention to provide means to seal the inner and outer casings, as the relative axial positions thereof are changed in response to changes in pressure and/or temperature within the inner casing.

It is also an object of this invention to provide a pump of the aforementioned type in which means controlling the seal of both the inner and outer casings are external to the outer casing.

Another object of this invention is to provide a pump of the aforementioned type in which packing for sealing both the inner casing and the outer casing can be inspected, tightened or replaced without dismantling the outer casing.

Objects and advantages other than those above set forth will be apparent as the description of the invention proceeds.

The novel features of the invention and how the objects are attained will appear from the specification and the accompanying drawing

2 showing an embodiment of the invention and forming a part of this application, and all these novel features are intended to be pointed out in the claim.

5 Referring to the drawing, the pump comprises an outer casing 10 divided into an intake chamber 11 and a discharge chamber 12 separated by an annular projection 13. An inlet passage 14 transmits liquid at intake pressure to the intake chamber 11. A discharge passage 15 transmits the liquid from the discharge chamber 12 at discharge pressure. The outer casing 10 is open at the discharge chamber 12 end of the casing. This open end is fitted with a casing cover 16 which is attached to the outer casing 10 by means of bolts 17, and a liquid tight seal is insured by a gasket 20 which is set in a recess 21 to avoid the possibility of blowing out. An inner casing 22 is inserted into the open end of the outer casing 10 and mounted therein. The casing 22 may comprise two axially extending halves bolted together according to the conventional practice of the prior art, as shown by the U. S. patent to Hollander, No. 1,655,546, to afford the structure 20 which can be easily assembled and disassembled. The radial shoulder 23 of the inner casing 22 is seated against the annular projection 13 within the outer casing 10. The inner casing 22 is held firmly against the projection 13 by the discharge pressure of the liquid within the discharge chamber 12. A gasket 24 is fitted between the shoulder 23 and the projection 13 to provide a liquid tight seal between the intake chamber 11 and the discharge chamber 12. Bolts 25 provide an initial seal and keep the inner casing 22 in position during periods of starting and stopping when the pressure within the discharge chamber 12 may not be enough to maintain the seal. Keys 26, 27 also aid in supporting the inner casing 22 in proper alignment, in that they keep the inner casing 22 from turning within the outer casing 10.

45 A shaft 28 is disposed in the inner casing 22 and extends through both ends of the outer casing 10. A series of annular passages 29 to 35 direct the fluid through the inner casing 22. Impellers 36 to 43 are mounted on the shaft in the annular passage 29 to 35.

The pressure of the fluid as it passes through the inner casing 22 is raised in a series of stages herein numbered 1 through 7. The first stage comprises two impellers 36, 37 both of which take suction from the intake chamber 11 and discharge into the passages 29 which direct the fluid to the opposite end of the inner casing 22, where the liquid enters stage 2. The liquid is then directed

through the remainder of the stages 2 to 1, which have a single impeller 38 to 43 in each, and the path of the liquid is indicated by the passages numbered 30 to 35. The fluid passes from the final pumping stage 1 to the passage 35 which discharges into the discharge chamber 12 of the outer casing 10 and the fluid is then discharged from the pump through the discharge passage 15. The arrangement and location of the stages is further described and claimed in the copending application of Edward J. Blackwell, Serial No. 123,719, filed October 26, 1949. As far as the invention of the present application is concerned, other arrangements may be used.

The arrangement and number of stages as illustrated results in having between stage 1 and stage 5, fourth stage pressure in the fluid passage 32 adjacent the passage 29 having first stage pressure therein, and between stage 7 and stage 4, seventh stage pressure in the passage 35 adjacent the passage 32 having fourth stage pressure therein. The high differential in pressure at these two locations requires suitable high pressure sealing means 81, 82 to reduce leakage of the high pressure liquid into the passage of lower pressure, resulting in a loss of pump efficiency. The construction of this high pressure sealing means 81, 82 may be of the form as here shown and more fully described and claimed in the copending application of Milton W. Lutz, Serial No. 123,856, filed October 29, 1949. As far as the invention of the present application is concerned, other sealing means may be used.

Means to allow axial expansion of the inner casing 22 relative to the outer casing 10, in response to changes in pressure and/or temperature within the inner casing 22 are herein disclosed as comprising a collar 50, an annular member 51, and sealing means. The sealing means are further disclosed as comprising glands 52, 53, a bleed off bushing 54, and packing 55, 56.

The collar 50 is spaced about the shaft 28 and is integral with the end wall of the inner casing 22. The annular passage 29 transmits the fluid from the two stage 1 impellers 36, 37 to the stage 2 impeller 38 at the opposite end of the pump. The intake for the stage 2 impeller 38 is within the area of the end wall enclosed by the collar 50. The member 51 is fitted to the collar 50 and attached thereto by bolts 57 that pass through a flange 58 extending radially from the member 51. The member 51 extends through an opening 60, of approximately the same diameter as the member 51, in the casing cover 16. The opening 60 is countersunk to provide space for the packing 55. The gland 52 fits about the outer diameter of the member 51 and bolts 61 provide the means for forcing the glands against the packing 55, thereby effecting a liquid tight seal between the inner surface of the opening 60 and the outer surface of the member 51 extending therethrough.

The inner diameter of the member 51 is larger than the outer diameter of the shaft 28 thereby providing space for the packing 56. A sleeve 62 is fitted to the shaft 28 and the bleed off bushing 54 is mounted about the sleeve 62 and fitted to the member 51 by an annular projection 63. A bushing retaining ring 64 is fitted to the member

51 and the bushing 54. Bolts 65 hold the ring 64 firmly to the member 51 and the bushing 54 is thereby securely held in place. Packing 56 is inserted in the remainder of the space about the shaft 28. Pressure is exerted upon the packing 56 by the gland 53 which is drawn up by bolts 66 fitted through the gland 53 and engaging the member 51. Liquid that passes the bushing 54 is bled off through a passage 67 and such liquid is reintroduced into the pump intake.

From the foregoing it will be apparent to those skilled in the art that the illustrated embodiment of the invention provides a new and improved liquid pumping machine and accordingly accomplishes the objects of the invention. On the other hand, it will also be obvious to those skilled in the art that the illustrated embodiment of the invention may be variously changed and modified, or features thereof, singly or collectively, embodied in other combinations than those illustrated, without departing from the spirit of the invention, or sacrificing all of the advantages thereof, and that accordingly the disclosure herein is illustrative only, and the invention is not limited thereto.

It is claimed and desired to secure by Letters Patent:

A double casing for a multistage centrifugal pump comprising: an integral outer pressure casing having an open end, an inner pump casing mounted in spaced relation within said outer casing, a shaft journaled in said inner casing extending axially therefrom to the exterior of said pump, an integral annular cover defining a single uninterrupted cylindrical internal surface radially spaced about said shaft, said cover being detachably secured to said open end of said outer casing to close said open end of said outer casing, said inner casing having end wall means terminating in an annular portion radially spaced from said shaft, a one piece annular member radially spaced about said shaft and attached to said inner casing end wall means, said annular member extending through said cover and being movable relative thereto in response to axial expansion of said inner casing, said member presenting a single uninterrupted cylindrical external surface complementary to said internal surface of said cover and cooperating therewith to withstand the full discharge pressure of said pump to atmosphere, first sealing means positionable externally of said cover cooperating with said surfaces to seal said annular member to said cover in all relative axial positions thereof, and second sealing means positionable externally of said cover for sealing said member against said shaft.

HUGH L. ROSS.
